UNITED STATES PATENT OFFICE

WILLIAM M. GOLDSMITH, OF CINCINNATI, OHIO, ASSIGNOR TO THE GOLDSMITH METAL LATH COMPANY, OF CINCINNATI, OHIO, A CORPORATION OF OHIO

METAL-TILE STRUCTURE

Application filed February 11, 1926. Serial No. 87,661.

This invention relates to metal tile structures for use in concrete flooring construction and has for an object the provision of a tile provided with means whereby said tiles may be assembled with strips of metal lath or other ceiling forming material on the ground and prior to positioning of the tiles upon a temporary support structure.

Another object is to provide a structure of this kind which is simple and inexpensive of manufacture.

Another object is to provide a structure of this kind which is easy to assemble and position.

Another object is to provide a tile unit of the class described by the use of which the usual concrete beams and floor may be provided and wherein the ceiling for the floor below in condition for receiving plaster, will be provided with the same operation.

These and other objects are attained by the means described herein and disclosed in the accompanying drawings, in which:

Fig. 1 is a perspective view of a flooring structure embodying tile units of my invention, parts being broken away.

Fig. 2 is a modified form of the tile unit of my invention.

As shown in Fig. 1 a supporting structure comprising shoring 8, stringers 9 and soffits 10, is erected and upon the soffit boards are positioned the units of my invention. Each unit comprises a metal tile 11 having usual side walls 12 provided with longitudinal straight edges 13. Upon each of the outer faces of the side walls 12 are provided a plurality of spaced lugs or mounting strips 14 spot welded, riveted or otherwise secured to the side walls as at 15. The mounting strips 14 or lugs 18 have a portion 16 extending beyond the longitudinal straight edges 13 of the tile to provide a securing means each of which may be provided with a plurality of spaced perforations 17 aligned at right angles to the sides 12 of the tile. The tiles 11 having mounting strips 14 thereon may be prepared at the factory and are readily nestable so that they may be conveniently packed and shipped.

In the modification shown in Fig. 2, a second series of lugs 18 may be provided on the

inner faces of the sides 12. The mounting strips 14 and lugs 18 may be of a comparatively light gauge metal and are therefore flexible so that they may be left to extend in parallelism with the sides 12 when the tiles are nested.

When it is desired to construct a floor and ceiling, the supporting structure, as heretofore described, has positioned thereon a plurality of the tile structures of my invention to which strips of metal lath 19 have been secured.

The securing of the metal lath or other ceiling material is performed upon the ground prior to positioning the tile and is accomplished by bending the portions 16 of the mounting strips about the longitudinal edges 20 of the sheets of ceiling material 19. When metal lath or other reticulated ceiling material is used, the soffits 10 may be provided with guide lines 21 and given ones of

the perforations 17 in the portion 16 may be positioned along the guide line 21 thereby materially facilitating positioning of the tiles and accurately determining the width of the beam to be formed between the sides of adjacent tiles. Nails 22 are then driven through the perforations 17 for retaining the tiles in their adjusted positions during the pouring of the concrete. This feature is shown and claimed in my copending application, Serial #87,130, filed February 9, 1926.

In the modification shown in Fig. 2 the strip of ceiling material is cut to a width substantially equal to the distances between the inner opposite faces 12 of the tile and the inner lugs 18 are bent inwardly to support said ceiling material. As shown in Fig. 2 the ceiling material comprises a sheet of gypsum board or other solid material, although either solid or reticulated ceiling material may be used with either of the modifications shown. In the modification shown in Fig. 2, the mounting strips 14 are used solely for accurately positioning the tiles 11 with guide lines 21 on the soffits 10.

After a floor has been poured and has become set, the support structure comprising shoring 8 and stringers 9 may be removed whereupon the soffits 10 are pulled down. The underside or ceiling which is thus formed

presents a true plane surface ready to be plastered without further preparation, since the plaster may be applied to the bottom surfaces of the beams and to the lath or ceiling board spanning the spaces between beams.

5 What I claim is:

1. A metal tile structure comprising a U-shaped tile having straight edges, a sheet of ceiling material extending between the straight edges of the tile, and bendable mounting strips on the tile and turned about the longitudinal edges of the ceiling material for associating the tile and lath.
- 10 2. In a device of the class described the combination of a U-shaped metal tile having straight edged side walls, bendable straps secured in spaced relation along the edges of said side walls, and a substantially flat sheet of ceiling material positioned in a plane with the straight edges of the tile and secured to the tile by bending said straps about the longitudinal edges of the ceiling material.
- 15 3. In a device of the class described the combination of a U-shaped metal tile having straight edges, straps on said tiles adapted to receive securing means for mounting the tiles, and a sheet of ceiling material disposed across the straight edges of the tile and secured thereto by bending the straps about opposed edges of said sheet.
- 20 4. In a device of the class described the combination of a U-shaped metal tile, a sheet of ceiling material positioned in a plane with the straight edges of the tile and bendable means on the tile adapted to be turned beneath the ceiling material for securing said material to the tile.
- 25 5. In a concrete floor in the course of construction, a series of soffit boards, a series of lugs secured in parallel rows on the soffit boards, a series of rows of metal tiles positioned in between adjacent rows of lugs and attached thereto and metal lath supported by the lugs beneath the tile.
- 30 6. The combination with a U-shaped metal tile, of a strip of ceiling material, and spaced means carried by the tile on opposite sides thereof for securing the ceiling material to the tile and for receiving holding means for securing the tile.
- 35 7. In a device of the class described the combination with spaced soffits of a U-shaped metal tile having depending straight edges, a sheet of ceiling material positioned in a plane with the straight edges of the tile and bendable members on the tile adapted for turning beneath the ceiling material for securing said material to the tile and for receiving fastening means whereby the tile is secured in between the soffits.
- 40 8. In a concrete floor and ceiling in course of construction the combination of temporary centering, lath inverted U shape tiles over the latch, the latch extending between

the lower edges of the tiles for providing a plaster receiving surface beneath the tiles, connector means between the lath and the tiles for fixing the lath to the tile and to preclude same against relative movement, fastening means for temporarily securing the associated tiles, lath and connector means to the temporary centering, and concrete extending around the tiles and permanently locking the tiles to the structure.

9. In a concrete floor in the course of construction, a series of soffit boards, a series of lugs secured in parallel rows on the soffit boards, a series of rows of metal tiles positioned in between adjacent rows of lugs and metal lath supported on the tile by the lugs.

In testimony whereof, I have hereunto subscribed my name this 5th day of February, 1926.

WILLIAM M. GOLDSMITH.

CERTIFICATE OF CORRECTION.

Patent No. 1,764,042.

Granted June 17, 1930, to

WILLIAM M. GOLDSMITH.

It is hereby certified that error appears in the printed specification of the above numbered patent requiring correction as follows: Page 2, line 65, claim 8, for the word "latch" read lath in both occurrences; and that the said Letters Patent should be read with this correction therein that the same may conform to the record of the case in the Patent Office.

Signed and sealed this 19th day of August, A. D. 1930.

(Seal)

M. J. Moore,
Acting Commissioner of Patents.
